UNITED STATES PATENT OFFICE.

CHARLES E. HAVILAND, OF LIMOGES, FRANCE.

DESIGN FOR TABLE-WARE.

SPECIFICATION forming part of Design No. 15.089, dated June 24, 1884.

Application filed January 31, 1884. Term of patent 14 years.

To all whom it may concern:

Be it known that I, CHARLES E. HAVILAND, a citizen of the United States, residing in the city of Limoges and Republic of France, have invented and produced a certain new and original Design for Table-Service, fully described and represented in the following specification and the accompanying drawings, forming a part of the same.

- 10 In said drawings only one of the many dishes necessary to compose a complete set of table-service is shown, the same being a dish or platter, illustrated in Figure 1 as provided with handles, and in Fig. 2 as without handles.
- 15 Fig. 3 represents an edge view or side elevation of the dish or platter shown in Fig. 1.

The characterizing feature of this design is a shape or configuration formed by the union of two leaves, each consisting of a single blade 20 involving a multiplicity of lobes having a sinuated crisped form. Each leaf may have multicostate veining, and exhibit between two of its lobes a stem or branch. To compose the dish two such leaves are joined together or 25 made to slightly overlap, according as the shape of the dish is to be more or less oblong. and the blade and lobes of the leaves will be more or less curled upward, according as the dish is to be deep or shallow.

- 30 In illustration of this design the fac-simile shows each leaf to have five lobes, respectively marked A, some of which may be more extended than others, if desired. The edges of the lobes have a sinuated crisped form, being 35 twisted, bent, or curled, as is shown, the degree of which twisting, bending, curling, and the like will vary according as the dish is shallow or deep along those portions that form free edges or edge-lines defining the portion 40 of one leaf overlapping another. In the drawings two such leaves, I, II, are shown as forming the dish, the leaf I overlapping the leaf II.

In Fig. 1 the stem B is shown as passing be-

tween two of the lobes of each leaf. In long dishes at least two such handles would be used, 45 while in small or round dishes one would suffice. When the veining is shown, the stem should be given a direction indicating its starting-point to be the point of generation of the said veining. Such dishes may or may not be 50 provided with covers involving the same design. Any fanciful surface-ornamentation may be delineated either by molding or painting. Thus veining, multicostate if desired, as shown, 55 may be employed, or any pattern that fancy may dictate or trade demand. These ornaments may be added without modifying the particular design embodied herein. The design, however, will be preserved whether the dishes remain white or are colored or decorated.

What is claimed is—

1. The design for the dishes of a table-service, the same consisting of a dish having the shape or configuration of overlapping leaves, the 65 lobes whereof have sinuous crisped edges, substantially as shown and described.

2. The design for the dishes of a table-service, the same consisting of a dish having the shape or configuration of overlapping leaves, 70 the lobes whereof have sinuous crisped edges, substantially as shown and described.

3. The design for the dishes of a table-service, the same consisting of a dish having the shape or configuration of overlapping leaves, 75 the lobes whereof have sinuous crisped edges, with stem-handle B, substantially as shown and described.

In testimony whereof I have hereunto set my hand in the presence of two subscribing witnesses.

CHARLES E. HAVILAND.

Witnesses:

E. CANDEAU,

F. CATE.
